UNITED STATES PATENT OFFICE.

IRVING MEAD, OF ROCKFORD, ILLINOIS.

BROODER.

Application filed August 16, 1926. Serial No. 126,531.

My invention relates to a brooder and particularly to the means for applying fresh air to the chick chamber and ventilating the same, as well as to the means for indirectly 5 heating said chamber.

The general object of my invention is to provide a brooder in which ample fresh air will be supplied at all times and in which the heating means employed beneath the 10 brooder cannot result in undesirable heating of the chick chamber or injury to the chicks.

The nature of my invention and its distinguishing features and advantages will 15 clearly appear as the description proceeds.

Reference is to be had to the accompanying drawings forming a part of this specification, it being understood that the drawings are merely illustrative of one example of the 20 invention.

Figure 1 is a perspective view of a brooder embodying my invention;

Figure 2 is a longitudinal vertical section without the runway for the chicks;

Figure 3 is a plan view of the brooder without the runway, and with the cover removed;

Figure 4 is a horizontal section on the line 4—4 of Figure 2.

In carrying out my invention in accordance with the illustrated example, a structure 10 forming the brooder body has double walls to form an air space 11 extending at the sides, ends and bottom of the body 30, see Figures 2 and 4. Beneath the brooder body 10 and shown as supporting the same is a base structure 12 adapted to accommodate a source of heat as for example a lamp 13. Above the lamp 13 and beneath 35 the bottom of the brooder body 10 a heat spreader 14 is provided held in place in any suitable manner. A ventilator 15 of known 40 form is provided on the removable cover 16 of the brooder body 10 which cover is usually sloping.

In the opposite ends of the brooder body 10 and extending through the double walls thereof are air inlets 17 controlled by slide 45 covers 18. The heat chamber or base 12 has an air inlet opening 19 controlled by a cover 20 having holes 21 for a restricted supply of air to said chamber. In addition to the air inlets 17 extending directly to the brooder chamber 22 through the double walls of the body 10, I provide an air inlet 23 leading to the space 11 and controlled by a slide cover

24. In the inner one of the double walls air holes 25 are formed at the ends and back and so located and in sufficient number as to afford ample inlet for air from the space 11 to the interior brooder chamber 22. Thus, 50 fresh air is supplied from the inlet 23 through the air holes 25 to the brooder chamber. In addition to the main ventilator 15 I provide ventilating openings 26 in the cover 16 at the corners of the brooder, there being fixed covers 27 over said ventilating openings 26.

Within the brooder chamber 22 at the corners, I provide vertical air baffles 28 which form triangular vertical air passages 29 in the corners of the brooder chamber 22. The lower ends of the baffles 28 are above the bottom of the brooder chamber 22 and said baffles terminate at the upper ends slightly 75 short of the cover or roof 16. The result is that much of the air passing into the brooder chamber 22 through the inlets 17 and air inlet holes 25, will be induced to take an indirect passage to and upwardly 80 through the vertical air passages 29, whereby fresh air will be continually and effectively disseminated throughout the brooder chamber before the air finally passes to the ventilator 15 and air vent holes 26. The 85 double bottom of the brooder chamber prevents the direct heating of the bottom of the chamber and protects the chicks. At the same time the double bottom wall serves to heat the air before it enters the chamber 90 22 and in this connection it is to be noted that the inlet hole 23 and the air inlet holes 25 are near the bottom of the brooder chamber. The air inlets 17 leading directly to the chamber 22 also are positioned in the 95 ends of the brooder body 10 adjacent to the bottom thereof where the greatest heat is present.

A run structure 30 is employed in practice at an end of the brooder body 10 so that the chicks may freely pass through the adjacent opening 17 to and from said run 30. An opening 31 is provided in practice at the end of run 30 and controlled by a closure slide 32 so that the chicks may be permitted to escape from the run 30 when desired.

I would state furthermore that while the illustrated example constitutes a practical embodiment of my invention, I do not limit myself strictly to the exact details herein illustrated, since, manifestly, the same can be considerably varied without departure

from the spirit of the invention as defined in the appended claims.

Having thus described my invention, I claim:

- 5 1. In a brooder, a body forming a brooder chamber and having double walls at the sides and bottom, a source of heat beneath the bottom, an air inlet leading through the double walls to said brooder chamber, an air inlet leading to the space between the walls, the inner wall having air inlets to permit air from said space and the said second inlet to enter the brooder chamber, said first-mentioned air inlet and said second-mentioned inlets being adjacent to the bottom of the brooder chamber, said brooder chamber having vents near the corners at the top of the brooder, and baffles forming vertical passages adjacent said vents, the lower ends of said baffles being above the bottom of the brooder chamber.
- 10 2. In a brooder, a body forming a
- 15
- 20

brooder chamber and having double walls at sides thereof and at the bottom, means supporting said brooder body elevated to accommodate a source of heat beneath the same, an air inlet leading through the double walls to said brooder chamber, an air inlet leading to the space between the walls, the inner wall having air inlets to permit air from said space and the second inlet to enter the brooder chamber, said first-mentioned air inlet and said last-mentioned air inlets being adjacent the bottom of the brooder chamber, said brooder body having vent means at the top; together with baffles forming vertical passages leading toward said vent means, the lower ends of the baffles being above the bottom of the brooder chamber, said vent means being located at the corners of the brooder body, and additional vent means at the top of the brooder body remote from the corners.

IRVING MEAD.
